PRESELECTOR TUNER

Andrew J. Kovach, Gary, Ind.

Application March 5, 1948, Serial No. 13,250

4 Claims. (Cl. 173—328)

1

This invention relates generally to radios and more particularly to an improved preselector tuner unit which may be used in conjunction with conventional radio broadcast receivers to tune to desired radio programs at predetermined times in accordance with selections made on a novel control card.

The tuner of this invention is particularly well adapted to control a receiver tuned on the standard broadcast band (550 to 1500 kilocycles) where programs are generally changed at exact quarter hour (or multiples thereof) intervals. With this tuner, programs may be selected in advance for a six-hour period, provision being made to turn the set on tuned to any one of a number of stations, to turn it off, or to select a different station at fifteen minute intervals throughout the period. By making slight changes in the control cards and associated mechanism the total period could be varied to cover an entire day and the selection interval made a different length.

Another object of this invention is to provide a preselector tuner which is a combination radio receiver and local oscillator unit that rebroadcasts a signal to a conventional radio receiver tuned to the rebroadcast frequency.

Another object of the invention is to provide a preselector tuner which can be incorporated as original equipment in a radio receiver or transmitter or as accessory equipment for existing radios or transmitters.

Another object is to provide an automatic preselector having a manual push button control which overrides the automatic control.

Another object is to provide a preselector unit which automatically deenergizes the radio set to which it is attached when no reception of any program is desired.

A further object is to provide a tuner in which all power consuming elements except the time clock are deenergized during those periods when no program is received, but which automatically energizes all its components as well as the radio being controlled when a program is to be received.

A further object is to provide a novel, inexpensive control card which may be readily set by punching to preselect the programs desired, which card can be used as an advertising medium if desired, or sold as replacement elements.

Another object is to provide a novel card in which conducting material printed upon the card serves to carry or control the current and circuits in the preselector tuning device.

Other and additional objects and advantages of

2

this invention will of course present themselves to those familiar with the art on reading the following specification in conjunction with the drawings and the appended claims.

- 5 In the drawings:
Fig. 1 is a schematic wiring diagram showing a portion of the circuit of this invention;
Fig. 2 is a wiring diagram showing the remainder of the circuit;
10 Fig. 3 is a view showing the novel control card;
Fig. 4 is a view of the back side of the card;
Fig. 5 is an end view showing the manner in which the card is folded;
Fig. 6 is an enlarged vertical section of a portion
15 of the card; and
Fig. 7 is a wiring diagram showing the electrical circuit which is the equivalent of the preferred form of control card.
- The circuit of this invention may best be understood by reference to Figs. 1 and 2 simultaneously. Fig. 1 shows predominately the tuning and selecting arrangement, while Fig. 2 shows the amplification, detection and output modulation stages.
- 20 25 The incoming radio waves are received by an antenna 10 (Fig. 2) and set up oscillations through the condenser 11 and the coil 12. From the coil 12 the waves are impressed through another condenser 13 on the control grid of a radio frequency amplifier tube 14.
- The plate of the tube 14 is connected through a condenser 15 to the control grid of the detector tube 16 and also through a coil 18 to the plate supply conductor 17. One set of the tuning variable condensers shown in Fig. 1 is connected to the points marked X—X' in Fig. 2. The second set of tuning variable condensers shown in Fig. 1 is connected to the points marked Y—Y' in Fig. 2.
- 30 35 40 45 The plate of the detector tube 16 is connected through a resistor 19 to the plate supply conductor 17 and through another resistor 20 and a condenser 21 to the control grid of a beam power amplifier tube 22.
- The output of the tube 22 is applied to a transmitting antenna 23 through a condenser 24. The plate is also connected through one winding of a transformer 25 and a condenser 26, in parallel, to the plate voltage supply. The secondary winding of the transformer 25 is connected in the cathode supply to the tube 22. Connected in this manner the tube 22 serves as an oscillator and generates oscillations according to the resonant frequency of the transformer 25 and condenser 26. These oscillations are in turn modu-

lated by the audio frequency output of the detector 16 so that a modulated radio frequency wave is applied to the antenna 23.

Thus the circuit shown in Fig. 2 receives radio waves, amplifies them, converts them to audio frequency, generates constant radio frequency oscillations, and modulates these oscillations to rebroadcast the incoming signal at a different constant frequency regardless of the frequency of the original waves.

The power supply is conventionally a half wave rectifier tube 30 being connected across the A. C. line and its output being filtered by a network to resistors 31 and 32 and condensers 33, 34 and 35 before being applied to the condutocer 17.

The filaments of the four tubes indicated at 36 are connected in series with a resistor 37 across the A. C. line 38 with electrical power controlled thereto as hereafter described. A potentiometer 40 is provided to adjust the output of the circuit.

The tuning and preselection portions of the circuit are shown in Fig. 1. Tuning is accomplished by inductance 45 and variable capacitances 46 selectively connected across the grid and cathode radio frequency amplifier tube 14 and matching inductance 47 and variable capacitances 48 connected across the detector tube 16. This portion of the tuning circuit is not unlike the conventional push button tuning circuits in general use, one tuning unit being provided for each station available for selection. For convenience of illustration, five station tuner units have been shown, but the number of units provided may be varied by merely paralleling the circuit shown or deleting some of the units.

Separate units are selectively connected to the circuit by relays 50 provided for each unit, each relay being illustrated as divided into two components 50 and 50a for purposes of convenience. The double throw switches 49 of components 50 are normally in a position wherein one end of the condenser unit 48 is short circuited to its other end. When energized, the shorted end of the respective condenser 48 is connected to a conductor 52 leading to the grid lead Y on Figs. 1 and 2. The other ends of the condenser units 48 are permanently connected to the common ground Y'.

The relays 50 however can be in actuality double relays comprising a double throw switch and a single throw switch both actuated by independent but series connected solenoids. The ends of the tuning condensers 46 are connected to the common pole of the double throw switch 51. The other poles of the double throw switches are connected to common ground X' which is normally contacted, and grid lead X which is normally open. The single pole switches 39 are normally open to be employed as self-holding switches in connection with the push button tuning arrangement.

From the above it will be seen that each tuning unit is normally shorted out of the circuit and connected only when its relay unit is energized. Thus it follows that the apparatus is automatically tuned to a given station when the corresponding relay unit is energized.

The relays 50 and 50a are preferably actuated by direct current and for this purpose a selenium rectifier 55 is connected in the line circuit from the extension cord plug or pronged connector 56. This rectifier permits only direct current to flow through the conductors 57, 58, 60 and 61 which carry the solenoid control current. A condenser 62 is connected across the rectifier 55 when the

solenoids are energized in order to smooth out the pulsating direct current produced by the rectifier.

From the rectifier 55 the conductor 58 leads to a switch 63 controlled by a time clockwork 64. This switch 63 is arranged so as to be closed momentarily each quarter hour by the clock 64 along with a switch 66 which produces a 110 volt pulse through electromagnet 59 to move a step switch 65 to the next position.

A relay 68 is provided which serves to connect the step switch 65 to the conductor 58 when closed. This relay 68 is provided with a holding connection 68a to keep the relay energized when the time switch 63 is open. Thus the common terminal of the step switch 65 is energized all of the time except when the relay 68 is deenergized as when the device is manually operated with push button control or a circuit beyond the step switch 65 is open, depending upon the control card 70 shown in Figs. 3 to 6, as will be described later.

In Fig. 7 the circuit equivalent to the card 70 is shown. From each terminal of the step switch 65 a plurality of conductors 71 extend to contactors 72. Each contactor 72 corresponds to a quarter hour period during the three hours contemplated by the card controls. The coils of each of the relays 50 are connected to a similar series of contactors 73 arranged in the card holder at right angles to the first series by conductors 74.

The card 70 shown in Figs. 3 to 6 comprises a folded piece of paper having lines of conducting material printed or stenciled thereon. One set of lines 75 corresponds to the contactors 72 when the card is folded, a line being provided for each quarter hour. The other set 76 perpendicular to the first and printed on the reverse side of the card corresponds to the contactors 73, one line being provided for each tuner unit.

If the card 70 were merely folded, no contact would be made between any of the conducting lines 75 and 76, but by bending out certain ones of precut tabs 78 and folding them back underneath as shown in Figs. 5 and 6 contact is made between separate horizontal and vertical lines. By proper location of the cuts and folded tabs 78, any horizontal time line 75 may be connected to any vertical station line 76.

Thus the card is set by bending out and folding tabs 78 to preselect certain programs for a given time. For this purpose indicia may be printed on the reverse side of the flap 70a as shown in Fig. 4 to aid in bending out the appropriate tabs 78. The other flap 70b may or may not be provided or used, but if it is provided it may be used for advertising instructions and as a protective cover for the conductors on flap 70a.

When a properly punched card 70 is inserted in the card holder (not shown) the electrical result is to connect individual terminals of the step switch 65 to individual relay coil leads 74, and when the step switch 65 is closed to a terminal which is connected to a relay lead 74 the corresponding relay 50 is energized. Due to the fact that when a particular relay unit is energized, its corresponding tuner unit is connected to the radio frequency stages of the circuit of Fig. 2, control of the output of the pre-selector unit depends on the position of the step switch 65 and the folding out of the card tabs.

Thus when the step switch 65 moves to a position where a relay lead 74 is energized the radio station to which the corresponding tuner unit is tuned will play for a fifteen minute interval. At

the end of this time the step switch 65 will move to the next position causing the relays 50 to be deenergized and the tuner disconnected. If a tab 78 corresponding to the next quarter hour period in the card has been punched, a relay unit will be energized for the next fifteen minutes and a second station will be heard.

In order to provide a manual push button control which will override the preselection on the card, a push button control switch 82 has been provided for each tuner unit. These switches are single throw single pole switches which are normally closed in one direction, opening when the buttons are pushed. The switches 82 are connected in series with a conductor 83 which delivers D. C. power to the solenoid 68. When any one of the switches 82 is pushed, the supply of current to the relay 68 is cut off and this relay closes in the opposite direction to energize a conductor 84 connected to other single pole single throw switches 79, each of which are normally open, but close to establish an energizing circuit through the relay coil leads 74 so that when a push button is actuated, control current is supplied directly to corresponding relay coils, the card 70 being by-passed. When the relay coils are energized in this manner they function in exactly the same manner as described above to control the tuning of the apparatus.

The single pole normally open single throw switches 69 of the relays 50 serve as holding switches to hold the relays 50 closed from the time the push button switch is momentarily closed until the end of the one quarter hour period. At the end of this period the time switch 63 functions to energize and close the relay 68 in the opposite direction and break the supply of current to the single pole elements of the relays 50.

Another relay 85 is connected so that its coil is always in series with the coils of the relays 50 so that the relay 85 is closed whenever any one of the relays 50 is energized. The relay 85 controls the supply of current to the conventional radio receiver (not shown) which is plugged into a receptacle 86 instead of into the wall outlet. When the relay 85 is closed the receptacle 86 is energized, as well as the radio tubes shown in Fig. 2 as per the line leads 38. Thus the conventional receiver and the preselector are turned on only when a program is to be received.

At the top of Fig. 1 the electrical equivalent circuit for another type of control card is shown. The card in this case is not shown but merely consists of a paper rectangle which has horizontal markings corresponding to each quarter hour interval and vertical markings corresponding to each station available for selection. To make selections, the card is merely punched to provide a hole at the intersection of the appropriate time lines and station lines.

In the card holder a pair of mating contactors is provided for each possible time and station combination. When a card is inserted, the pairs of contactors are prevented from touching except where a hole has been punched in the card. In Fig. 1 the pairs of contactors are indicated at 90 and the card at 70. Actually the rows of contactors 90 corresponding to separate stations are parallel rather than in line as shown. If, in Fig. 1, the rows of contactors 90 connected to each of the conductors 14 were rotated so as to lie along a line perpendicular to the paper, the actual arrangement would be approximated. The electrical functioning of this modified ar-

rangement is substantially the same as the preferred embodiment described above.

From the above description of my invention it will be seen that a novel preselector tuner has been provided which may be adapted to control any conventional radio receiver or transmitter within the stated objects, without the necessity of modifying the receiver, and programs are pre-selected by the novel control card, including the reception of frequency modulated broadcast as well as amplitude modulated broadcasts.

Although several embodiments of this invention have been described, it is not intended that the invention be limited to this embodiment, and changes or modifications such as will occur to those familiar with the art may be made without departing from the spirits of this invention whose scope is defined by the following claims.

What is claimed is:

1. A card of insulating material having two parallel folds therein dividing the card into three approximately equal portions, a plurality of spaced vertical lines of conductive material on the center portion, a second plurality of spaced horizontal lines of conductive material on one of the side portions, said pluralities of lines being on opposite sides of the card so as to be insulated from one another when the card is folded, the unlined side of the card serving to enclose and insulate one of said pluralities of lines, and punched reversely folded tabs on one of said portions for making electric contact through the card from lines of one plurality to lines of the other.

2. A card of insulating material having a fold therein dividing the card into two adjacent lying portions, a plurality of spaced parallel lines of conductive material on one portion, a second plurality of spaced parallel lines of conductive material on the other portion, said pluralities of lines being perpendicular to each other and on opposite sides of the card so as to be insulated from one another when the card is folded, and punched reversely folded tabs on one of said portions for making electric contact through the card from lines of one plurality to lines of the other.

3. A card of insulating material having two parallel folds therein dividing the card into three portions, a plurality of spaced parallel lines of conductive material on the center portion, a second plurality of spaced parallel lines of conductive material on one of the side portions, said pluralities of lines being perpendicular to each other and on opposite sides of the card so as to be insulated from one another when the card is folded, the unlined side of the card serving to enclose and insulate one of said pluralities of lines, and punched reversely folded tabs on one of said portions for making electric contact through the card from lines of one plurality to lines of the other.

4. A substantially rectangular card having two parallel folds therein dividing the card into a first side portion, a middle portion, and a second side portion, one edge of said card being outwardly offset along the middle portion to provide a projection thereon and said folds being so disposed that the first side portion is narrower than the middle portion, a plurality of spaced parallel lines of conductive material on the front face of the middle portion extending onto said projection, a second plurality of spaced parallel lines on the rear face of the second side, and punched

uent-over tabs in one of the lined portions for making electrical contact between individual conductors on opposite faces of the card, the lines of conductive material on the middle portion being covered by the side portions except for the ends of said lines on said projection and the lines on the second side portion except the ends near the fold line being covered by the first side portion when the side portions are folded inwardly over the middle portion.
